UNITED STATES PATENT OFFICE.

WILLIAM RHOADES, OF SAN LEANDRO, CALIFORNIA, ASSIGNOR, BY DIRECT AND MESNE ASSIGNMENTS, TO RHOADES SHALE OIL COMPANY, A CORPORATION OF CALIFORNIA.

APPARATUS FOR EXTRACTING OIL FROM SHALE.

Application filed December 3, 1923. Serial No. 678,231.

This invention relates to improvements in apparatus for the extraction of oil from shale, and particularly to the proper apparatus for carrying out my process of oil extraction as disclosed in my copending application for Letters Patent executed under even date herewith, filed under date of December 3, 1923, and Serial No. 678,230.

The objects of the invention are to provide a simple apparatus, easily managed and which will recover a large percentage of the volatilizable matter held in the shale.

The drawing accompanying this specification illustrates the preferred form of my apparatus, Figure 1 being a vertical section taken through the center, and Figure 2 is a section of the retort as seen looking down from the line 2-2 of Figure 1.

The figures show at (1) a retort having a fire pot (2), distillation chamber 1^a, sight tubes (3) arranged transversely through the fire pot and distillation chamber, internal draft regulator and vapor take-off (4), shaker grate bars (5), gravity material delivery chute (6), preheating jacket (7) for the incoming material, pipe (8) from suction flues to the preheating jacket, take-off pipe (9) from the lower part of preheating jacket to an exhaust fan (10), a discharge pipe (11) from the fan leading to any suitable condensing and separating system not shown, as forming no part of the invented improvements.

Within the preheating jacket around the gravity feed chute is a spiral fin (15) to force the hot vapors to circulate around the chute on their way to the fan (10). The fan (10) may be complete with its power unit, or may be driven by a belt (22) from a motor (21).

The take-off pipes (4) take the form of crossed pipes; as shown in Figure 2, extending through the retort and having openings (13) arranged along their under sides. Within the pipes (4) are other separate pipes (16) having similar openings (17) adapted to coincide with the others, and the pipes (16) are longitudinally adjustable within the outer ones by means of hand wheels (18), having stems threaded through the closed ends of the pipes (4), as shown, and engaging the inner slideable pipe, so that the openings are adjustable for varying the draft suction. The openings (13) are

kept toward the under side of the pipes (4) to prevent filling of the pipes with the descending shale being treated.

It is evident without illustration that the inner pipes could be revolved to vary the opening instead of being longitudinally moved.

In operation, a fire is first kindled in the fire pot with any suitable fuel, and the shale in comminuted form (14) is fed through the chute to fill the retort, the fan meanwhile being set in motion to create a draft upward through the fire and through the imbedded take-off pipes 4.

The adjustment of the draft should be such as to keep the zone of greatest heat in the region of the sight tubes (3), their varying redness as seen by looking through them being indicative of the condition and position of the fire, and the shaker grate will require manipulation to continuously drop the burned material and thereby cause a steady descent of the shale within the retort.

The operation of the grate bars may be done manually by an attendant in the smaller installations or better by automatic means, especially in the larger installations. Many forms of such means are now extant, and in the drawing is shown one actuated by a shaft (19) driven by worm gearing (20) from the motor (21) which drives the fan (10).

The grate bars are double, the lower set being fixed and the upper one being slideable thereover guided by stems (23) and (24), the latter being pivoted at (25) to a lever (26) slotted at (27), and engaging at its lower end (28) a grooved cam on the shaft (19) whereby the constant rotation of the shaft causes a constant oscillation of the grate. The lever (26) is pivoted in its slot to a slideable fulcrum stand (29) to permit adjustment of the stroke to suit conditions.

As the motion of the lever (26) is very slow it may be disengaged until the fire is well under way by simply pulling out the loose pin (25). The retort is provided with suitable fire doors and ash pit doors or discharge chutes as may be desired, no particular importance being attached to any such well known construction.

In functioning to extract the oil from the shale, the heat volatilizes the oils in a distillation chamber just above the fire and the

gases are drawn off through the pipes 4, passing spirally around the feed chute, thence through the fan and ejected for condensation in any desired form of condensing apparatus not forming a part of this invention.

The preheating of the shale drives off some of the moisture and feeds heated shale to the retort, thus preventing the volatilized vapors from recondensing within the incoming material to a tarry mass, and the fire is maintained on the fuel residue remaining in the shale after extraction of the more volatile constituents.

Having thus described my invention, it will be apparent to those skilled in the art that many changes can be made in the arrangement of the parts and details of the apparatus, and any such as may come within the scope of my invention are intended to be covered in the appended claims.

I claim:

1. In a retort for driving off volatile matter from oil shale, a pipe extending into the shale within the retort having openings therein and suction means connected to the pipe for drawing the volatilized matter into the pipe through the openings, and means for varying the area of said openings.
2. In a retort for driving off volatile matter from oil shale, a pipe extending into the shale within the retort having openings therein and suction means connected to the pipe for drawing the volatilized matter into the pipe through the openings, and means for varying the area of said openings, said latter means comprising a pipe within the first pipe and having coinciding openings and means for displacing the inner pipe in relation to the outer pipe.

3. In an apparatus for extracting oil from shale, a retort with means for supporting the shale therein for combustion, means for feeding shale to the retort, piping extending into the shale within the retort for extracting matter volatilized by the heat of the combustion and connected to the suction of a pump, said piping between the pump and retort being arranged to carry the hot extracted vapors around the shale being fed to the retort for preheating the material, and the discharge of the pump being directed to a condensing system.

4. In apparatus for recovering oil from shale, a retort, means for supporting the shale within the retort for combustion, a gravity chute for feeding shale to the retort, means extending into the retort for drawing off vapors distilled therein by the heat of combustion, means for guiding the distilled vapors spirally around the chute and including a jacket arranged around the chute and in spaced relation thereto and a spiral tin located between the chute and jacket, the said jacket having an inlet at one end portion and an outlet at its opposite end portion.

5. In an apparatus for extracting oil from shale, a retort with a shaker grate adapted to support a bed of shale for combustion, a perforated pipe extending into the shale above the combustion area within the retort, a power actuated suction fan arranged to draw gases into the pipe through the perforations, means for shaking the grate and operating the fan and means for varying the length of the shaking stroke while maintaining a constant speed of the fan.

WILLIAM RHOADES.
